GAS HEATING DEVICE

Richard J. Rutherford, Worcester, Mass., assignor
to Worcester Gas Light Company, Worcester,
Mass., a corporation of Massachusetts

Application November 15, 1938, Serial No. 240,464

4 Claims. (Cl. 126—350)

The present invention relates to a combination heating and hot water unit which may be used in the fire pot of a coal range or which may be incorporated in a similar type stove or in a heating stove or range.

It is now quite common practice to convert coal ranges for the use of fuel oil or so called range oil for the purpose of eliminating ashes and dust resulting from the use of coal and for the purpose of obtaining a more efficient and easier operated kitchen range. Oil for this purpose has for the most part proved to be quite successful, although it has certain objectionable features. It frequently has objectionable odors. The oil is apt to spill when filling the tank and sometimes the burner is quite difficult to light and adjust properly. Other fuels have been tried for this same type of work but without any apparent commercial success and among these are gas burners, although for the most part burners using gas have proved to be expensive for general common use.

In the present invention the applicant has perfected a unit in which the fuel is gas, and which may be used both for heating water and for warmth in the room or place where the heater is situated. The unit has particular utility in summer, fall and winter heating and for this purpose the unit may be operated intermittently or continuously in the various combinations as will appear from the specification below.

The unit also operates with an efficiency comparable to that of the range oil burners, particularly with respect to the cost of operation.

In the present system the unit may be operated in two or three positions which corresponds to what may be called summer, winter and spring or fall heating and operation. In winter heating the burner supplies most of its heat for general heating purposes, namely for heating the room or space where the stove or heater is located. In this position of operation a small portion of the heat from the burner is supplied to produce hot water in a storage tank, storage boiler or the like. In this method of operation the system is so adjusted in this position of operation that with the burner operating intermittently to maintain a constant room temperature, through a thermostat control from some place in the room, the storage tank or boiler may be maintained at the average warm temperature of 140° to 150°.

For more rapid heating of the storage tank the unit is operated in a second position in which the flames and gases from the burner pass directly

over the water heating coils within the unit and thereby heat rapidly the water circulating in these coils from the storage tank or boiler. A thermostatic device is usually provided in the intake line of the heater, which thermostatic device is connected for operation of the gas supply valve to the burner for turning off the gas supply. If the unit is allowed to remain in this operating position all of the water in the storage tank may be heated beyond the upper allowable temperature. In other words when all of the water has reached a certain temperature in the storage tank, the thermostatic device automatically turns off the gas supply. Ordinarily a full tank of hot water is not necessary so that after the heater has been burning for a short time, it may either be turned off or operated in one of the other positions for instance, general heating purposes, other than for heating water.

Various methods of operation will be discussed below in connection with the description of the unit, and other objects and advantages of the device according to the present invention will be more fully learned from the description of the embodiment of the invention in the specification when read in connection with the drawing attached hereto, in which:

Figure 1 shows in perspective a range with a fragmentary section showing the gas unit therein.

Figure 2 shows a vertical section of the unit.

Figure 3 shows an end view of a portion of the unit as seen from the right of Figure 2.

Figure 4 shows a modified construction of a detail of the unit for operating the unit externally of the stove, and,

Figure 5 shows a further modified construction of the device as viewed from a position substantially the same as Figure 3.

In Figure 1 the stove may be any conventional type in which the fire pot 2 is provided at one side and the heating oven 3 at the other side. The top covers 4 may be positioned in the usual places on the top face of the range and the ordinary flue passages and dampers, neither of which is shown in the figure, may be used.

The gas unit 5 including both the burner and the top heating box may be positioned either on an intermediate platform as is sometimes provided in some coal ranges, or the unit may be provided with legs 6, 6, 6, 6, in the case where the unit stands on the ash chamber floor. It will be evident of course that the unit may be provided with proper fixtures so that it can conveniently be installed for any of the usual ranges.

The gas burner 7 which extends substantially the length of the heating unit, is positioned slightly below the water box 8 and is supported preferably from the cross bracket 9 which may be attached to the frame supports 10, 10. The gas burner 7 is supplied through a gas supply 11.

As indicated in Figure 1 the supply to the burner may be controlled by a valve or valves which may be operated in the supply line 11 to provide thermostatic control of the burner.

This arrangement is preferably used for generally heating in which case the water box 8 is closed and the burner 7 allowed to operate to maintain the room temperature constant.

15 When the room temperature has reached the desired value, the thermostat in the room operates through a suitable device to the connection 11 and the burner goes out until the temperature drops to whatever lower limit the thermostat is set for.

This intermittent operation of the burner 7, in accordance with the design of the unit is such as to provide sufficient hot water for the storage tank or boiler for ordinary use. As stated this hot water is approximately at a temperature of from 140° to 150° F.

The burner is equipped with a thermostatic pilot 12 which would operate to turn off the gas supply to the burner in the event the pilot light was extinguished. Gas is supplied to the device through line 14.

The box 8 which is positioned directly over the burner 7 contains a plurality of water circulating pipes which will be presently described.

The pipes are positioned substantially parallel to each other and extend the length of the water box. They are connected to one another externally of the box by means of the U shaped sections 17 and 18 at the front end 16 of the box

40 and 19 at the rear end of the box, so that as the circulating water enters through the inlet 15 at the rear, it is first circulated through the lower of the two parallel pipes, one of which, 20, is shown in Figure 2, and then through the upper of the two parallel pipes, one of which 21 is shown in Fig. 2.

The connection 19 at the rear end of the box as indicated in Figure 2, sends the circulating water from the lower pipes upward to the upper set of pipes. Any number of pairs of pipes may

50 be included in the box depending upon the size and the amount of heating surface that is desired for the particular system. Within the box each pipe is provided with a great number of radiating elements 22, 22, 22, which preferably are integral with the wall of the pipe itself.

55 These elements are shaped like porcupine quills and project from the pipe in a fashion similar to a brush, making a very dense baffle in the space surrounding the pipes, providing however sufficient freedom for the circulation of the hot gases upward through the box.

The top of the box is preferably provided with a cover 23, so that the exhaust gases must pass through the side slots 24 just beneath the cover at the top of the side walls.

60 This direct circulation of the hot gases over the water coils of the type described, makes it possible to extract the heat from the gases very efficiently and quickly.

In the operation of the device in the position

70 in which the gases pass directly through and around the pipes, the water heating is of course effected most rapidly in the system. For this position, the lower baffle plates 25, 25, are extended downward in the dotted line positions indicated in Figure 3. When the baffles are in the

position indicated by the full line, in which position the direct flame and gases from the burner 7 are diverted by the plates, the heating of the pipes within the box 8 is obtained indirectly through the external side walls of the box. The 5 hot gases of the burner 7 in this last position of operation pass mainly around the outside of the box and up through the flues of the range in the usual manner.

The control of the position of the lower baffles 10 25 is effected through a link system which will presently be described. The baffles 25 are pivoted by a rod 26 mounted to allow free motion in holes in the upright plates 27, 27. The free ends of the baffles 25 are supported through a 15 rod 28, each to a link 29 which are pivoted to a second link 30 at the pivot 31. The link 30 is attached at its other end to a bell crank lever 32 pivoted at 33 to the upright plate 27. The bell crank lever 32 is provided with a weight 34 20 so that the lever may be raised either in the full line position or lowered to the dotted line position 34 indicated in Figure 3. In the full line position the lower baffles 25 come together as has been stated and closes the openings over the 25 burners while in the dotted line position the link 30 is forced downward which forks outward the links 29, opening the lower end of the box extending the baffles 25 slightly outward beyond the lower part of the box thus tending 30 to concentrate even more the heat and flames of the burner 7.

The bell crank lever 32 is positioned wholly within the fire box and may be operated preferably by opening the top lids 4, reaching down with a poker or some other such device and tipping the bell crank lever to a position indicated by the dotted or full lines in Figure 3, providing respectively moderate heating or full heating of the water coils.

If desired the arrangement shown in Figure 4 may be employed for controlling the operation of the bell crank lever 32 externally of the stove. In this modification the lever 32 is mounted to the upright plate 27 of the box by means of a rod 45 35 which is permanently fixed to the bell crank lever and is extended through the plate 27 as indicated at 36. The rod is held in place by means of the cap 38 on the inside end of the plate 27. The rod 35 extends through the wall 39 of the 50 stove and has attached at the external side of the stove, a lever 40 by which the bell crank lever may be positioned to keep the baffles 25 either opened or closed.

In the arrangement indicated in Figure 5, a 55 somewhat different modification is shown. In this case the baffles 41 are similar to the baffles 25 in Figures 1 and 3. They are pivoted or hinged to the side brackets 42, 42, and operated by means of the pivot links 43, 43, which are attached at 60 their upper end to the control bar or plate 44. This control plate 44 moves vertically up and down within a strap or collar 45 attached to the wall 46 of the coil box. The plate 45 is provided for operation in three different positions with 65 two notches 47 and 48 at the sides of the plate 44 and an end enlargement 49 at the end of the plate 44. The operator simply adjusts the position of the baffles by reaching in the top of the fire box with a poker or some other tool, lowering 70 or raising the arm 44 and hanging it with one of the notches on the strap or collar 45 or allowing the arm or plate to be lowered until the head 49 rests on the collar 45. In this last position the baffles 41 extend outward to the sides of the 75

box, directing and confining the flames and the hot gases within the box and compelling them to pass upward over the heating coils. In the position where the upper notch 48 hangs over the strap 45, the baffles are partly closed, which may be a condition of operation of the unit in moderately cool weather where hot water is regularly wanted. In the highest position of the bar or plate 44 as indicated in Figure 5, the box is entirely closed and the least heat is supplied to the heating coils. This last position in general corresponds to winter operation when the burner is operating for greater periods of time, and therefore the water pipes will have a longer period of time in which they will be heated. Direct supply of heat under this last position is not so necessary, since the water pipes will be heated for a longer period of time than in the previously described intermittent operations.

20 It will be appreciated of course that while the system may be entirely automatically controlled, the best method of operation is to provide also manual control so that at any time any desired method of operation may be used. Particularly 25 if it is desired to have hot water quickly, the burner may be turned on full and the baffles completely opened. An automatic safety device is provided for limiting the boiler temperature when operating under these conditions, in which case 30 as has been previously explained the thermostat control will operate to turn off the gas burner. This combination may be employed together with a means for producing a constant room temperature in which case under conditions when the 35 baffles are closed the room thermostat will operate to turn off or on intermittently the burner to keep the room temperature constant at its desired value.

If under these conditions it is desired to provide 40 quickly a quantity of hot water, it is simply necessary to open up the baffles and set the burner for continual operation, which will automatically be discontinued when the maximum allowable temperature is reached in the boiler. If the automatic operation is allowed to continue the burner 45 will operate intermittently until the boiler temperature becomes so hot that the thermostat will turn the burner off. Other modifications and variations than those herein described will obviously suggest themselves to those skilled in the art. The box for insertion in the fire pot is here indicated as elongated and rectangular. Variations in shapes and sizes may be made provided the construction does not part from the purpose 50 and utility of the invention.

Having now described my invention, I claim:

1. In combination an independent heating and hot water unit adapted to be installed in a fire pot of a coal range or the like, comprising a 50 closed box having a plurality of water circulating pipes positioned therein having means on the surface thereof supplying a substantially large heat radiating surface, said box being provided with a flue vent near the top thereof above the circulating pipes, a gas burner positioned directly below said box and adapted to supply heat thereto, means hinging the bottom of said box and means positioned at the front of said box having an operating lever and links structurally connected to 55 said hinging means for either directly exposing said pipes to said burner when the bottom of the

box is opened or diverting the direct heat of the burner from said pipes when said bottom is in a closed position.

2. In combination an independent heating and hot water unit adapted to be installed in a fire 5 pot of a coal range or the like, comprising a closed box having a plurality of water circulating pipes positioned therein having means on the surface thereof supplying a substantially large heat radiating surface, said box being provided with a flue vent near the top thereof above the circulating pipes, a gas burner positioned directly below said box and adapted to supply heat thereto, the bottom of said box comprising a pair of baffles, means for hinging each of said baffles substantially at the lower sides of said box, said baffles having such a width that when fully opened they extend approximately to the level of the gas burner, and means having links pivoted to the ends of said baffles and an operating lever connected thereto all positioned at one end of said box for extending the ends of said baffle outward laterally beyond said burner or raising said baffle to a position closing the bottom of said box between the burner and said pipes. 20 25

3. An independent hot water unit adapted to be installed in a fire pot of a coal range or the like, comprising an elongated rectangular casing having a flue vent at the top side thereof, a plurality of water circulating pipes positioned there- 30 in having means forming large radiating surfaces and pipes running lengthwise of said casing, a pair of plates at the bottom of said casing, means for hinging said plates at one side to the side of said casing, said plates adapted when closed to 35 form a cover at the bottom of the casing and when open to expose said water pipes to a gas burner positioned directly beneath said casing, said plates in an open position extending approximately to the level of the gas burner but laterally 40 at the side thereof, and means including a plurality of linked elements attached to the non-hinged side of said plates for positioning said plates either in an open or closed position.

4. An independent heating and hot water unit 45 adapted to be installed in a fire pot of a coal range or the like, comprising an elongated rectangular casing having a flue vent at the top side thereof, a plurality of water circulating pipes positioned therein having means forming large radiating 50 surfaces, said pipes running lengthwise of said casing, a pair of plates at the bottom of said casing, said plates adapted when closed to form a cover at the bottom of the casing and when open to expose said water pipes to a gas burner positioned directly beneath said casing, said plates in an open position extending approximately to the level of the gas burner but laterally at the side thereof, and means for positioning said plates either in an open or a closed position, comprising 60 a pair of links pivoted at one end thereof to the non hinged side of said plates, a single link joining and supporting said links together at the other end thereof and a bell crank lever pivoted at its fulcrum to said casing and at one end to the free 65 end of said single link and having a weight thereon whereby said plates may be placed either in their open or closed position by operation of said bell-crank lever. 70
